N. F. BUCKLEY,

HYDROCARBON BURNER.

APPLICATION FILED OCT. 14, 1918.

NICHOLAS F. BUCKLEY, ^{INVENTOR}

UNITED STATES PATENT OFFICE.

NICHOLAS F. BUCKLEY, OF LOS ANGELES, CALIFORNIA.

HYDROCARBON-BURNER.

Specification of Letters Patent.

Patented Dec. 2, 1919.

1,323,825.

Application filed October 14, 1918. Serial No. 258,069.

To all whom it may concern:

Be it known that I, NICHOLAS F. BUCKLEY, a citizen of the United States, residing at Los Angeles, in the county of Los Angeles and State of California, have invented a new and useful Hydrocarbon-Burner, of which the following is a specification.

This invention relates to hydrocarbon-oxygen burners and may be used in connection with an air-pressure tank, or a cylinder of oxygen gas, or a special steamer providing water in form of steam-gas, or vapor; particularly adapted for burning of crude petroleum of asphaltum base, so as to afford a complete and perfect oxygenation and combustion of all the carbon molecules which otherwise escape free and unburned, causing a smoking flame known as "soot" or "lamp-black."

One object of the invention is to provide some simple and practical burners which are particularly adapted for the use of crude petroleum of either asphaltum or paraffin base, or their various derivative fluids of light or heavier gravity, as well as for use of any fuel in liquid form.

Another object is to provide a burner which will fit on any stove for cooking and heating; also on baking ovens up to the largest size of steam bakeries, etc.; also for hot-water furnaces, steamers and boilers of any description; such burners individually adapted for the different hydrocarbon fluids of various gravity and density, which could not otherwise be burned to advantage all through the same burner-head.

Another object is to eliminate the objectionable deficiencies and drawbacks of the present day burners on the market, which do not offer a satisfactory means for substituting crude oil or any other liquid fuel, by providing different burner heads or orifices to be attached for the different oils.

Another object is to provide means by which the fuel as well as air and oxygen can be injected through the burner-head before mixing with the air in the combustion chamber.

Other objects will appear from the following description and appended claim as well as from the accompanying drawing, in which—

Figure 1 is a vertical longitudinal section through the device.

Fig. 2 is a top plan view of the device.

In Fig. 1, 3 designates the base plate to

which the different detail parts are attached, or in relation to which the several detail parts are arranged to give the results as hereafter described. The base plate is provided with an opening 4 through which the air supply pipe 5 is disposed, having a funnel 6 provided on its lower end and allowing the air supply to discharge into the air-chimney or flue 7, which forms in this device the retort for preheating the air. The cups, pans, or receptacles 8 are provided for igniting the oil when starting the burner. Practically concentric to the cups 8, the burner necks 9 are projecting upwardly forming the means for securing the burner-heads and several supply connections. The burner heads 10 are removably and exchangeably disposed over the burner necks 9, a suitable number of suitable form of burner heads or gas jets are supplied to the device for use with different gravity fuel. The air supply pipes 11 are disposed through the burner necks 9 from below terminating suitably so as to discharge the air into the burner head or gas jet 10. The fuel supply pipes 12 terminate within the air supply pipes 11, and smaller air or oxygen supply pipes 13 terminate within the fuel supply pipes. The free ends of the air-supply pipes constitute the intake funnels 14. The free ends 15 of the fuel supply pipes are communicating with the connections 16. The free ends 17 of the smaller air supply pipes 13 are inserted sidewise through the connections 16 terminating in the funnels 18. To hold the upper ends of the fuel supply pipes within the air supply pipes 11 in their concentric position, and the smaller air pipes in their concentric position within the fuel supply pipes 12, small bosses or projections 19 are provided on the outside of the smaller air supply pipes 13 and on the outside of the fuel supply pipes 12, slightly touching the inner walls of the surrounding next pipes, as will easily be understood. The free ends 20 of the air retort 7 terminate a suitable distance above the burner heads or gas jets 10.

When starting the burner, a little fuel oil is admitted into the cups 8 for preheating the air coming through the air-retort 7. As soon as a proper gasifying occurs between the air from the discharge ends 20 of the air retort 7 and the fuel oil in the cups 8, fuel oil is admitted through the supply pipes 12, and from then on a proper mixing is regu-

lated through the air retort 7 and through the fuel supply 12 as well as through the extra supply pipes 11 and 13. Suitable valves or throttles can, of course, be provided at suitable points in all supply pipes, though not shown, as will easily be understood.

5 The smaller air supply pipes 13 are especially provided to inject steam or oxygen 10 through the gas jets or burner heads, at a point where such is most useful.

To provide for surplus air in certain fuel 15 oils of different gravity, the side arms 21 are arranged so as to supply extra air from the sides of the air retort 7 at about the point indicated at 22. Other arms 23, indicated in dotted lines, may be provided at the opposite side of the retort 7. Thus, I wish it understood that I do not limit myself to the specific form shown in the drawing, but that 20 the air may be supplied from any suitable point or part as long as the mixing is procured between the free ends of the air retort and the burner head, in combination with 25 the different supply pipes within connection from below the burner head, as described above.

I prefer to make the air-retort 7 of fire clay, graphite, magnesite, volcanic ash, bone ash, or some other fire proof and heat retaining mineral.

Having thus described my invention, I claim:

In a hydrocarbon burner, a base having an opening for an air supply and two burner jets on opposite sides of the air supply opening, and an air supply pipe projecting through the opening in the base terminating in elbows above the base a suitable distance above the burner jets the air supply pipe 35 projecting through the opening in the base plate naturally forming the center supply end, side supply ends being provided on the air supply pipe besides the center supply end communicating with the supply 40 pipe at practically right angles to the elbows, all substantially as described.

In testimony that I claim the foregoing as my invention I have signed my name in the presence of two subscribing witnesses. 50

NICHOLAS F. BUCKLEY.
